UNITED STATES PATENT OFFICE.

HARRY G. JENNISON, OF TOLEDO, OHIO.

WOOD-BLOCK PAVEMENT.

1,395,829.

Specification of Letters Patent.

Patented Nov. 1, 1921.

Application filed July 23, 1919. Serial No. 312,851.

To all whom it may concern:

Be it known that I, HARRY G. JENNISON, a citizen of the United States of America, residing at Toledo, Lucas county, Ohio, have invented new and useful Wood-Block Pavements, of which the following is a specification.

This invention relates to flooring or pavements of wood having peculiar advantages 10 for adaptability in wide ranges of weathering operations, not only for shrinking, but for expansion.

This invention has utility when incorporated in uniformly shaped impregnated 15 wood paving blocks.

Referring to the drawings:

Figure 1 is a fragmentary view in section of a pavement embodying the invention;

Fig. 2 is a fragmentary plan view of the 20 pavement of Fig. 1;

Fig. 3 is a section showing the anchoring or sealing action of the blocks to the pavement as herein disclosed;

Fig. 4 is a perspective view of one of the 25 blocks;

Fig. 5 is an enlarged detail view in plan of the spacing means with adjacent ducts or reservoirs in the position as laid;

Fig. 6 shows the spacing means of Fig. 5 30 when subjected to slight compression;

Fig. 7 is a more advanced stage of compression of the device of Fig. 5;

Fig. 8 shows the spacing means pushed down into flush position; and

Fig. 9 shows the blocks as subjected to 35 contraction.

The pavement base 1 may, preferably, be of a hard or firm material as concrete configured for the camber or final curved surface 40 form of the pavement as desired, but therebelow. Of course, in bridgework the foundation may be of wood or timber instead of concrete, as may be desirable. In the latter instance, it may be acceptable to coat the timber bridge foundation or flooring with tarred paper and over this tarred paper place mastic 2 as a coating. This coating 2 may be directly placed on the concrete 1 and extend fully between the curbs 45 or felly guards.

Creosoted impregnated wood blocks 4 may be placed in parallel rows extending transversely of the pavement. The blocks of

these rows may preferably have the arching of the age rings 5 extending length-wise of the block. The joints between the ends of the blocks are staggered from one row as to the other row as shown in Fig. 2. Furthermore, these end joints of the blocks are spaced by V- or wedge-shaped lugs 6 shown herein as defined on each side by a V-groove 7. This lug 6 is herein shown as integral and accordingly has the grain of its portion extending in the same direction as the grain of the wood of the block and through 65 fully from the pavement top to the base of the block or coating 2. Owing to the general arching relation of the age rings 5 of the blocks 4, the length of the block is the portion susceptible to the greater tangential 70 expansion of wood, being about 7% as against a radial expansion of some 4% in long leaf yellow pine even when creosoted.

While a creosoted block may normally be construed as an expanded block, under 75 weathering conditions there arise problems involving even additional expansion and this is cared for by the pavement of this disclosure. The V-lug 6 is of such contour as readily to respond to the action of the 80 block 4 in moving toward an adjacent block in closing the joints between two ends of blocks in a common row. If the narrow or pointed portion of the lug 6 does not enter the adjacent block, it may be crushed down 85 by the face of such adjacent block, the nature of this action being due to which of the portions of the wood may be more soft.

What may or may not be the extent of exudation of impregnation material due to 90 this crushing action on the lug 6 is rather difficult to foretell. However, in laboratory operations a quick crushing may bring about a slight bead or drop 8 of impregnation material, as shown in Fig. 5, while if this crushing be followed up rapidly, this bead will slightly enlarge as shown by drop 9 in Fig. 6. A complete crushing of a triangular lug 6 of an area forming an equilateral triangle of $\frac{1}{2}$ " altitude and brought to condition 100 flush with the block as shown in Fig. 7 would not expel impregnating material from the block of an area greater than $\frac{1}{4}$ sq. in. when such compression occurs in a period of time not exceeding five minutes in laboratory operations when there has been a two 105

stage full cell impregnation of 12# per cu. ft. In laboratory manipulations, a recovery of the lug, when the pressure is released, occurs almost to full size in the course of less than half an hour when the crushing has been rapid and the release prompt thereafter.

Of course, in actual paving conditions there would be a much greater time interval. However, in practice it has been noted that lugs approximate original form after shrinkage has occurred, which shrinkage has been preceded by lug crushing expansion action of the blocks in the pavement.

15 The blocks are further provided with means isolating the blocks and for anchoring the blocks against relative movement on the coating 2 of the foundation 1. This means is herein shown as additional lugs 11 projecting from the longer side of the block 4 and bounded by grooves 7 cutting into the face of such longer side of the block 4 and also cutting the longer arc age rings 5 of the block 4. These lugs 11, accordingly, 20 are on a side adjacent the lugs 6 and as so uniformly arranged upon the oblong blocks of uniform contour effect a spacing of the transverse rows from each other as well as the blocks from each other in a common 25 row. The lugs 11 may act similarly to the lugs 6 but of course normally would not be subjected to so much strain as the lugs 6 on matters of expansion. The grooves 7 adjacent the lugs 11, however, have additional or 30 rather more effective action over the grooves 7 adjacent the lugs 6 for these grooves adjacent the lugs 11 in cutting the longer arc age rings 5 in block contraction have a tendency 35 to check as shown by supplemental grooves 40 12 in Fig. 8. This checking or opening of the block 4 is very slight because it is distributed to occur as herein shown in several places, and as so distributed, the rigid un-grooved side of the block 4 is a firm holding 45 of the block to approximate its normal full-length condition, thereby maintaining the position of the block as a complete pavement element with no tendency to disturb the position of such element as anchored on the 50 50 the mastic 2 upon the foundation 1.

In the laying of the pavement the spacing of the blocks as herein disclosed permits an introduction of filler completely around each block involving connecting or flow portions 55 13 (Fig. 3) from the supply ducts or reservoirs 14, by which such filler is readily introduced to effect a complete anchoring of the block 3 to the pavement base coating 2. This portion 14 is accordingly a reserve supply 60 60 which in the common row of the joints between the blocks may respond to come and go between the blocks for a long period.

At the time of pouring or squeegeeing this 65 65 filler between the blocks, the ducts or grooves 7 would normally be filled approximately

flush with the upper face of the pavement, but this quantity would gradually weather or settle down to heighten the connecting portion 13 and lower the duct or groove portion 14 of the filler. This lowering may permit the entrance of some road or floor dirt between the blocks in the narrow spacing. Of course, if very coarse material were wedged between the blocks, such would interfere with the expansion take up of the 70 75 block. However, in practice it has been found that such road dirt or floor material, if fine, may be fluxed or caused to flow out by the filler or by the exudation of impregnation material of the blocks effect a mastic 80 therewith and thereby allowing of the expansion takeup action of the blocks of the pavement. This has even occurred in instances of fine sand filler.

The contour of the lugs 6, 11, is such that 85 there is in action a really weaker lug of a broad base, the grooves in a measure protecting the lugs, notwithstanding the lugs are weakened. Tests in practice indicate that this weakening of the lugs for the actual 90 effective lug area as protruding from the side of the block may be as much as fifty per cent. as compared with the same size lug which does not have the adjacent groove.

Accordingly, there is provided by the 95 block of this disclosure a pavement involving a minimum of the use of wood even to shallow block height of 2" with insured spacing for the block and insured anchoring of the block in a pavement with a mastic 100 filling involving operative expansion takeup as well as effectual contraction minimizing features.

As has been endeavored to bring out here- 105 in due to the anchoring effectively of the wood blocks to the surfaced base, such blocks may be of minimum height and still hold up against shear from traffic. In pouring or squeegeeing the filler which may be 110 considered as hot tar or pitch, this liquid material coming in contact with the lower temperature side walls of the paving blocks at once chills and has a resultant surface tension tending to clog filler from flow into sealing position. The spacing of the blocks 115 by the lugs 6, 11, in a measure relieves the detrimental action of this surface tension. However, the grooves 7 effectively act even in cold weather in relieving the surface tension of the filler so that the filler may flow 120 to connect with the mastic coating 2 on which the blocks are placed. Affinity or cohesion with the slow flow nature of the substance then takes its course in completing and maintaining the sealing of the block. 125

Notwithstanding the effective expansion takeup provision in the blocks 4 as provided by end lugs 6 in the laying of a pavement on its foundation it is not inconsistent to provide expansion joints 15 as an addi- 130

tional safeguard which joints may be disposed as desired, being shown in Fig. 1 as adjacent curbs 3.

What is claimed and it is desired to secure by Letters Patent is:

1. A rigid grain up wood paving block having on two vertical sides thereof integral V-shaped lugs continuous with adjoining V-shaped grooves, forming a W in cross-section with a high central apex, the grooves on one of the faces of the blocks intercepting the arching portion of longer arc age rings on the blocks.
2. A paving block having parallel base and wear faces, sides extending therebetween, and a lug on one of said sides projecting beyond the plane of said side and springing from grooves inward from the plane of said side.
3. A pavement block provided with filler receiving ducts, and block spacing means protruding beyond a side of the block adjacent said ducts, said block spacing means extending upward from the base of the block to the wear face of the block, and said ducts being reentrant into the block side and extending parallel with the spacing means.
4. A wood paving block comprising a block abutting face, a lug protruding from said face, and, in addition to the normal projection of the lug from the side of the block, adjacent reentrant groove means further reducing the resistance of the lug.
5. A pavement wood block having lateral contraction dissipating groove means extending as to the apex of the V-groove from the base of the block to the wear face of the block, said means intercepting the long arc age rings of the block arching from the opposite rigid block side, and end expansion take-up lug means, whereby in assembling said block in a pavement a plastic filler may coact in the regions of said contraction and expansion means to maintain the block 45 in a sealed held position.
6. A pavement wood block having spacing means for forming a joint with another block, and embodying a lug defined by adjacent grooves into the block from the side of the block from which the lug extends, said grooves broadening the base of said lug.
7. A wood paving block having a side, lug means on said side protruding therebeyond for laterally spacing the block from an adjacent block, said lug means having identified as a part thereof a base of greater cross-section than the cross-section of the lug in the plane of said block side, said 60 base being defined by groove means widening said lug inward from the plane of the block side.
8. A pavement oblong block having a side thereof provided with a block spacing lug isolated from said block face by grooves, said lug effective to space said block side from an adjacent block, and said grooves taking up shrinkage and providing ducts to the block base from the block face, and an additional side of said block having a groove isolated lug effective to space said additional side from a third block, whereby anchoring means coating said sides may be deposited in the grooves as reserve reservoirs for fully sealing the block on different sides in a pavement.
9. A pavement block provided with spacing means, and in addition thereto and adjacent thereto, groove forming surface tension relieving means for a block filling liquid filler.

In witness whereof I affix my signature.
H. G. JENNISON.
